UNITED STATES PATENT OFFICE.

JAMES EDWARD PIERCE, OF ALBION, MICHIGAN, ASSIGNOR TO UNION STEEL PRODUCTS CO., INC., OF ALBION, MICHIGAN.

RECEPTACLE AND THE LIKE.

1,203,258.

Specification of Letters Patent.

Patented Oct. 31, 1916.

Application filed February 24, 1916. Serial No. 80,314.

To all whom it may concern:

Be it known that I, JAMES EDWARD PIERCE, a citizen of the United States, residing at Albion, county of Calhoun, State 5 of Michigan, have invented certain new and useful Improvements in Receptacles and the like, of which the following is a specification.

This invention relates to improvements 10 in receptacles and the like.

In receptacles, such as are used by bakers for the mixing of dough and commonly designated as "dough troughs," it is desirable to provide a rim which shall be 15 rounded and without creases or crevices which would collect material and become unsanitary. My improvements are especially designed by me for use in receptacles or troughs of this character which are of 20 considerable size and I have illustrated the same in the accompanying drawing as I have embodied them for the market in a "dough trough." My improvements are, however, of quite general application and 25 are desirable for use in other receptacles, particularly those of considerable size.

The main object of this invention is to provide an improved receptacle provided with a rim which has the effect of being 30 integral with the body and at the same time a receptacle which is quite economical to produce.

Further objects, and objects relating to structural details, will definitely appear 35 from the detailed description to follow.

I accomplish the objects of my invention by the devices and means described in the following specification.

The invention is clearly defined and 40 pointed out in the claims.

A structure which is a preferred embodiment of my invention is clearly illustrated in the accompanying drawing, forming a part of this specification, in which:

45 Figure I is a side elevation of a "dough trough" embodying the features of my invention. Fig. II is a detail vertical section on a line corresponding to line 2—2 of Fig. I, showing the form of the rim and the 50 means for securing the same to the body. Fig. III is a detail horizontal section through one corner of the rim taken on a line corresponding to line 3—3 of Figs. I and IV. Fig. IV is an enlarged detail section on a line corresponding to line 4—4

of Figs. I and III. Fig. V is a perspective view of one of the rim side members.

In the drawing similar reference characters refer to similar parts throughout the several views, and the sectional views are taken looking in the direction of the little arrows at the ends of the section lines.

Referring to the drawing, the receptacle body 1 is usually formed of sheet metal, the structural details of the body however, are not shown, as they form no part of this invention. The body is provided with a rim comprising side members 2 and corner members 3. The side members 2 are tubular, being preferably formed of tubes having longitudinal slits at the inner sides, the lower edges of the slit being offset inwardly at 4 so that the outer edge 5 constitutes a shoulder. This outer edge 5 is disposed to abut the edge of the body 1, as clearly shown in Fig. II. The offset portion is offset a distance equal to the thickness of the metal of the body, so that when the edge 5 is arranged to abut the body the offset portion 4 lies against the side of the body. The edge of the body and the edge of the rim members are welded throughout, as indicated at 6, thus closing the joint and effectively securing the parts together. This welding may be done by hydrogen flame or electric welding, or otherwise, as desired.

It will be noted that when the edge 4 is offset the rim member has the general shape of a scroll and may be formed of strips of metal rolled into the scroll form illustrated.

At the corners I provide the joint or corner members 3 which are angled castings shouldered at 7 to receive the ends of the side members 2 and having downwardly facing shoulders 8 on their inner sides abutting the upper edges of the body and welded thereto.

The corner members and side members are preferably welded together so that they constitute a substantially continuous rim. With the parts thus arranged, I secure a round rim which is of considerable diameter and one which is round and has no pieces likely to collect or retain material.

Structures embodying my improvements are comparatively simple and economical to produce and are attractive and finished in appearance.

I have only illustrated my improvements as I have embodied the same in receptacles

used for dough troughs, the adaptation or embodiment however to receptacles of different shape will be readily understood by those skilled in the art to which my invention relates.

Having thus described my invention, what I claim as new and desire to secure by Letters Patent, is:

1. In a structure of the class described, 10 the combination of a receptacle body and a rim therefor comprising tubular side members having longitudinal slits at their inner sides and having their lower edges offset inwardly substantially the width of the metal 15 of the body, said side members being disposed with their outer edges abutting the edges of the body and with the sides of their said offset portions against the sides of the body, the abutting edges of said body and 20 rim members being welded throughout thereby securing them together and closing the joints, and angled corner members having shouldered ends fitting into the ends of said side members and having downwardly 25 facing shoulders on their inner sides abutting the upper edges of said body and welded thereto.

2. In a structure of the class described, 30 the combination of a receptacle body and a rim therefor comprising scroll-shaped side members disposed with their outer edges abutting and welded to the edges of the body and with their sides against the sides of the

body, and angled corner members having shouldered ends fitting into the ends of said side members and downwardly facing shoulders on their inner sides abutting and 35 welded to the upper edges of said body.

3. In a structure of the class described, 40 the combination of a body member and a tubular rim having a longitudinal slit at its inner side and having its lower edge offset inwardly substantially the width of the metal of the body, said rim member being disposed with its outer edge abutting the 45 edge of the body member and with the side of its said offset portion against the side of the body, the abutting edges of said body and rim members being welded throughout thereby securing them together and closing 50 the joint.

4. In a structure of the class described, 55 the combination of a body member and a scroll shaped rim member disposed with its outer edge abutting the edge of the body member with its inner edge against the side of the body member, said abutting edges being welded throughout thereby securing them together and closing the joint.

In witness whereof, I have hereunto set 60 my hand and seal in the presence of two witnesses.

JAMES EDWARD PIERCE. [L. s.]
